UNITED STATES PATENT OFFICE.

SAMUEL H. PERRON, OF MENDON, MASSACHUSETTS, ASSIGNOR TO ALEXANDER STEINERT, OF BOSTON, MASSACHUSETTS.

MUSICAL INSTRUMENT.

Application filed December 8, 1921, Serial No. 520,860. Renewed June 28, 1927.

This invention relates to musical instruments and has particular reference to player pianos having means for obtaining various degrees of expression by means as a note sheet having perforations or the like to govern the sounding of the notes and other perforations or the like to govern the quality or expression of the notes sounded.

In a copending application filed July 12, 1921, Serial No. 484,257, I have disclosed a player piano having means for obtaining various degrees of expression and having means by which a plurality of note sheets having differing systems for obtaining degrees of expression may effect the control of the piano to give a rendition of the notes represented by the expression perforations in the note sheet. For instance, certain well known types of note sheets each have different systems of expression perforations and the apparatus disclosed in said application is adapted to be controlled effectively by all of said types of note sheets.

The key or striker pneumatics of the player action are connected, through control valves, with a wind chest; and the wind chest is in communication, through expression-controlling means, with a source of suction as a pump.

In order to effect the independent control of the bass and treble notes, the wind chest is usually divided into two parts, with the striker pneumatics adapted to control the lower half or bass notes of the piano connected with the bass side of the wind chest and the striker pneumatics adapted to control the upper half or treble notes of the piano connected with the treble side of the wind chest. The suction in the two parts of the wind chest is adapted to be regulated independently whereby normally to accentuate the treble over the bass notes.

In different types of reproducing pianos, each of which may be arranged for control by a particular type of note sheet, the divisions of the wind chest are or may be different for each type of piano. The wind chest of one piano, for instance, may be divided between the 46th and 47th notes; of another, between the 44th and 45th notes; and of another, between the 43rd and 44th notes. There are usually three notes the positions of which vary with the types of

pianos enumerated and the note sheets adapted to be associated with said instruments are perforated in accordance with the position of said notes in either the bass or treble division of the wind chest.

A reproducing piano of the type set forth in my above-named co-pending application and having a wind chest division corresponding, say, to one system and set to play, say, a type of roll not adapted to that system, may strike some notes as, say, the 44th, 45th and 46th notes with a shaded or undesired expression, inasmuch as the roll may be perforated for expression control from the treble side of the wind chest while the particular system of division employed on the piano may place them on the bass side of the wind chest. While, in many musical compositions these particular notes do not occur and while, in other compositions, the shaded expression is not ordinarily apparent to the average listener, yet it is desirable to obtain a faithful rendition of these notes as recorded on any type of note sheet which the piano is arranged to play.

An object of this invention is to provide a musical instrument, as a reproducing piano, with means to control pre-determined notes from either the bass or treble side of the wind chest, at will.

A further object of the invention is to provide predetermined striker pneumatics with means by which the control thereof may be effected from either the bass or treble side of the wind chest, at will.

A further object is to provide means by which the control of predetermined striker pneumatic may be shifted from the bass to the treble side of the wind chest simultaneously with the conditioning of the expression system whereby to arrange the piano for the playing of selected types of note sheets.

A further object is generally to improve musical instruments adapted to play note sheets having different systems for control of the instrument.

Fig. 1 is a diagrammatic view of a control system for a piano embodying my invention.

Fig. 2 is a diagrammatic view similar to Fig. 1, and illustrating a modified means for effecting the control of predetermined

striker pneumatics from the bass and treble sides of the wind chest and also illustrating a modified connection between the wind chest selector valve and the tracker bar selector 5 valve.

Fig. 3 is a diagrammatic view, in section through the wind chest, striker pneumatics, primary valves, and tracker.

Fig. 4 is an enlarged detail of the wind 10 chest with the pouch board removed and illustrates the divisions between the valves of the middle striker pneumatics of the wind chest.

Fig. 5 is a view similar to Fig. 4 and illustrates the manner in which two of the striker pneumatics may be connected within the wind chest.

Fig. 6 is an enlarged sectional detail of the wind chest taken along line 6-6 of 20 Fig. 4.

As here shown, my invention is applied to the player system including the tracker bar 10, the tubes 11 leading from the tracker bar to the pouches 11^a of the primary valves 25 12, the wind chest 13 having the secondary valves 14, controlled from the primary valves through the tubes 15 and pouches 15^a and the striker pneumatics 16 controlled by the secondary valves. The wind chest has 30 a bass compartment A through which approximately the lower half of the striker pneumatics are controlled; and said compartment A is connected with an expression controlling device 17 by means of the tube 18 for regulation of the expression of the accompaniment notes. The wind chest has a treble compartment B through which the remainder of the striker pneumatics are controlled; and said compartment B is connected with the expression controlling device 17 by means of the tube 19 for regulation 35 of the theme notes. Said expression controlling device is connected to a source of suction, as the pump 20, by means of the tube 21. The arrangement above outlined is more or less common practice. In some types of reproducing pianos, the primary valves 12 are omitted and the tracker ducts are placed directly in communication with the pouches of the secondary valves in an 40 obvious manner. My invention may be applied to both arrangements.

The wind chest 13 is provided with a pouch board 25 which forms a removable 45 cover for the bass and treble compartments A and B, and bears the pouches 15^a for the secondary valves.

In accordance with my invention, I provide means by which certain striker pneumatics may be governed for accompaniment and theme, at will, whereby to condition the wind chest and associated mechanism to correspond to conditions under 50 which different types of note sheets are made.

In carrying out the invention, I provide a wall 26 which is extended between and in airtight engagement with the walls of the wind chest and which is adapted to be in airtight engagement with the pouch board 70 25. Said wall may be arranged in the wind chest between, say, the 43rd and 44th notes, or the valves controlling the corresponding striker pneumatics for said notes. With this arrangement all notes below the 44th 75 note will be controlled from the bass compartment A of the wind chest, and corresponds to the division in the wind chests of pianos adapted to be controlled by two well known types of note sheets. 80

I also similarly arrange a second wall 27 to divide the wind chest between the striker pneumatics corresponding, say, to the 46th and 47th notes so that all notes above the 46th note will be controlled from the treble 85 compartment B of the wind chest, whereby to condition the piano for control by a different type of note sheet. I further provide walls 28 and 29 extended between and in airtight engagement with said walls 26 and 27 on each side of the valve 14^c corresponding, say, to the 44th note. This arrangement of walls serves to divide the wind chest not only into the bass compartment A and treble compartment B but also into the additional 90 compartments c, d and e which are placed in communication with appropriate striker pneumatics by means of the valves 14^c, 14^d and 14^e which may correspond, say, to the 44th, 45th and 46th notes respectively. 95

Means are provided for placing said compartments c, d, and e in communication with the bass compartment A and treble compartment B, or what is the equivalent, for control from the expression controlling 100 device 17 for accompaniment or theme, as desired.

To condition the system to cooperate in playing a certain type of roll, compartments c, d and e may be associated with the bass 110 compartment A. For, say, second type of roll the compartment c may be associated with the bass compartment A and the compartments d and e with the treble compartment B. For, say, another type of roll all 115 compartments c, d and e may be associated with the treble compartment B. For types of rolls other than those herein enumerated, a similar procedure may be followed.

It will be noted that in the specific arrangement herein set forth, said compartments d and e are shifted together from the bass to the treble side of the wind chest and therefore may be considered, in effect, one compartment and are so connected. The 125 connection between the compartments may be effected externally of the wind chest, as will hereinafter be described, or it may be effected within the wind chest. This latter arrangement is illustrated in Fig. 5 in which 130

the pipe 30 is disposed within the treble compartment B serves to establish communication between said compartments *d* and *e*. Duplicate tubes 31 are brought out beyond the wind chest from the compartment C and are connected to the junction box 32. Duplicate tubes 33 are extended from compartment *d* and duplicate tubes 34 are extended from compartment *e* beyond the wind chest. Said tubes 33 and 34 are connected to a common junction box 35 by which both compartments are placed in communication. Due to the restricted depth of the compartments A and B the duplicate tubes illustrated are provided in order to eliminate a throttling effect on the striker pneumatics associated with said compartments *c*, *d* and *e*.

Means are provided to associate said chambers *c*, *d* and *e* with the bass and treble compartments A and B respectively, or what is the equivalent, with the bass and treble sides of the expression controlling device 17, at will. Said means includes the stationary valve block 36 having the aligned recesses 37 and 38 in its upper face. Said recess 37 is connected by the tube 39 with the tube 18 extended from the bass compartment A of the wind chest to the bass side of the expression controlling device 17. Said recess 38 is connected by the tube 40 with the tube 19 extended from the treble compartment B of the wind chest to the treble side of the expression controlling device. A movable valve block 41 is slidably received upon the upper face of said block 36 to cover the recesses therein; and said movable valve block may be moved on said stationary block by suitable means as the lever 42 and the connecting link 43. Said movable valve block is arranged to remain in any position in which it is moved by said lever 42.

A flexible tube 44 is carried by said movable valve block 41 and is in communication with a duct extended to the lower face of said block by which it may be placed in communication with said recesses 37 and 38 of the stationary valve block. Said tube extends to and is in communication with the junction block 32 and consequently with said compartment *c*. A similar flexible tube 45 is carried by said movable valve block adjacent said tube 44 and extends to and is in communication with the junction block 35 and consequently with the compartments *d* and *e*. Preferably said tubes are larger in internal cross-section than the pipes 31, 33 and 34, to avoid a throttling effect.

In the position of the movable valve block 41 illustrated in Fig. 1, both tubes 44 and 45 are in communication with the recess 37 of the stationary valve block and consequently all of said compartments *c*, *d* and *e* are connected with the bass compartment A and the bass side of the expression controlling device 17 by means of the tubes 39 and 18. In

such a position, the wind chest may be conditioned for the playing of, say, the Welte type of roll.

When the movable valve block 41 is so moved as to place the tube 45 in communication with recess 38 while the tube 44 remains in communication with the recess 37, the compartment *e*, remains associated with the bass compartment A of the wind chest while the compartments *d* and *e* are connected with the treble compartment B of the wind chest by means of the tubes 40 at 19. This arrangement may condition the wind chest for playing one particular type of roll. A further movement of the movable valve block 41 in the same direction places both tubes 44 and 45 in communication with recess 38 and the compartments *c*, *d* and *e* in communication with the treble compartment B. This arrangement may condition the wind chest for playing another type of roll. Said recess 38 is or may be made of length suitably to admit of further movement of the movable valve block 41 in the same direction without modifying the communication of said tubes 44 and 45 with said recess for a reason hereinafter to be set forth.

I may divide the vacuum chamber 47 of the primary valves in a manner similar to the dimension of the wind chest above set forth but ordinarily this will not be necessary and I find that good control of the primary valves is obtained by connecting the vacuum chamber 47 directly with a suitable source of suction, as the pump 20, through the tube 48.

The wind chest and associated apparatus above set forth is adapted to be associated with means to condition the expression controlling devices of the piano for effective control by note sheets having differing systems of expression perforations or the like and as set forth in my above-named copending application.

In said application the tracker is provided with expression ducts adapted to register with the expression perforations of a plurality of different types of note sheets, as the Ampico, Duo-Art, etc., and selector means are provided to connect with selected expression devices predetermined tracker ducts corresponding with the expression perforations of a selected type of note sheet, and discard or render ineffective all other expression ducts. I have illustrated my present invention in combination with such means.

Selector valve boxes 50, 51, 52 and 53 are provided, one for each different type of note sheet to be played. Four are here shown. Tubes 50^a, 51^a, 52^a and 53^a extend from the expression ducts in the tracker bar 10 to said valve boxes 50, 51, 52, and 53, and said tubes 50^a etc., are connected only with the expression ducts adapted properly to reg-

ister with the expression perforations in the type of note sheet for which the valve boxes 50, etc., have been selected.

Appropriate tubes 50^b, 51^b, 52^b, and 53^b lead out of said valve boxes 50, etc., and extend to suitable expression controlling devices. For simplicity but one tube 50^b is shown connected with expression controlling devices, and said tube is here illustrated diagrammatically as extending to a primary valve 54; and a tube 55 extends from said valve to the expression controlling device 17.

Pouches 56 are disposed in said selector valve boxes 50, etc., and, when atmospheric pressure is behind them, serve to cut off communication between said tubes 50^b, etc., and 50^b, etc. Said pouches are controlled by means of the tubes 50^b, 51^b, 52^b and 53^b. Said tubes are here shown, Fig. 1, as extended to the stationary valve block 36 and placed in communication with aligned ducts extended to the upper face of said blocks. A flexible tube 57 is connected with a suitable source of suction, as the pump 20, and is carried by said movable valve block 41 and is arranged to be moved successively into communication with said tubes 50^b etc. By this means suction may be established behind the pouches in any selected selector valve box to place the tracker bar ducts associated therewith in operative control of selected expression control devices. That part of the valve controlling the selector valve boxes may be a separate selector valve-box selecting valve and connected with the wind chest selector valve by suitable means, see Fig. 2, by which the selection of the expression ducts in the tracker bar and connections of the wind chest for a selected type of note sheet may be effected simultaneously.

In Fig. 2, I have illustrated a slightly modified arrangement of selector valves for the wind chest and tracker bar.

The wind chest is divided, as above set forth, into the bass compartment A, the treble compartment B, and the compartments c, d and e. The wind chest selector valve is here shown as structurally independent of the tracker bar selector valve and includes the stationary valve block 60. A movable valve block 61 is arranged to slide over the upper face of said stationary block; and said movable valve block is provided with the recesses 62 and 63 in its lower face. A tube 64 is brought out of the wind chest from the chamber c and is in communication with a duct extending through the stationary valve block, in the left-hand end thereof, and a branch tube 64^a extends from said tube 64 to a similar duct in the right-hand end of said stationary valve block. A tube 65 is brought out from the compartment d and is in communication with a duct in the righthand end of the stationary valve block. A branch tube 65^a extends to a sim-

ilar duct in the lefthand end of said block. Said compartment e is placed externally in communication with said compartment d by means of the tube 66 which is connected with said tube 65 externally of the wind chest. A tube 67 extends from the bass compartment A of the wind chest and communicates with a duct in the left-hand end of said valve block and a similar tube 68 extends from the treble compartment B to the righthand end of the valve block.

Said right and left hand ducts in the valve block are arranged in two aligned groups and the said movable valve block 61 is arranged to be moved to place its recesses 62 and 63 in communication with all or with a part of the ducts in said groups whereby to place the compartments c, d and e selectively in communication with the bass or treble compartments in an obvious manner.

The tracker bar selector valve, in this modification is structurally independent of the wind chest selector valve and includes the stationary valve block 70 having aligned ducts with which the tubes 50^b, 51^b, 52^b and 53^b are in communication, as before. The movable valve block 71 is provided with a duct with which the flexible tube 57 is in communication, and said tube extends to a suitable suction source, not shown. Said valve block 71 is movable to place the tube 57 selectively in communication with said tubes 50^b, etc., to effect the selection of desired expression ducts in the tracker bar, as before.

A control lever 41^a is operably connected with said movable valve block 71 by suitable means as the connecting link 42^a and is also operably connected with the movable valve block 61 of the wind chest selector valve by suitable means, as by the rack 72 and gear sector 73. The arrangement is such that a movement of the lever 41^a serves to move the movable blocks of both selector valves in a suitable direction and to a suitable extent to effect the simultaneous conditioning of the wind chest and the tracker bar and associated expression devices to play a selected type of note sheet.

It is obvious that the invention may be otherwise modified without departing from the spirit thereof.

I claim:

1. In a musical instrument, the combination of an expression controlling system, means to condition said system for effective control by different types of note sheets, striker pneumatics, and means to group said striker pneumatics in various predetermined combinations for effective control by different types of note sheets.

2. In a musical instrument, the combination of an expression controlling system, means including selector mechanism to condition said system for effective control by different types of note sheets, striker pneu-

matics, means including selector mechanism to group said striker pneumatics in various predetermined combinations for effective control by different types of note sheets, and 5 means connecting said selector mechanisms for conjoint operation.

3. In a musical instrument, the combination of an expression controlling system, means including a selector valve to condition 10 said system for effective control by different types of note sheets, striker pneumatics, means including a selector valve to group said striker pneumatics in various predetermined combinations for effective control by 15 different types of note sheets, a manually-operable control device for said valves, and

means connecting said valves with said control device for conjoint operation.

4. In a musical instrument, the combination of an expression controlling system, 20 means including a selector valve to condition said system for effective control by different types of note sheets, a wind chest having a plurality of compartments, striker pneumatics associated with said pneumatics, 25 means including a valve to interconnect said compartments selectively to correspond with different types of note sheets, and means to adjust said valves simultaneously.

In testimony whereof, I have signed my 30 name to this specification.

SAMUEL H. PERRON.
